UNITED STATES PATENT OFFICE.

HENRY B. NICHOLS, OF PHILADELPHIA, PENNSYLVANIA, ASSIGNOR TO WILLIAM D. GHERKY, OF PHILADELPHIA, PENNSYLVANIA.

GRINDING-MACHINE.

1,035,129.

Specification of Letters Patent.

Patented Aug. 6, 1912.

Original application filed December 22, 1910, Serial No. 598,840. Divided and this application filed December 28, 1911. Serial No. 668,323.

To all whom it may concern:

Be it known that I, HENRY B. NICHOLS, a citizen of the United States, residing at Philadelphia, in the county of Philadelphia and State of Pennsylvania, have invented a certain new and useful Improvement in Grinding-Machines, of which the following is a specification, reference being had therein to the accompanying drawing.

10 This specification is a division of my application, Serial No. 598,840, filed December 22nd, 1910, on a "grinding machine."

The present application relates particularly to the construction and arrangement of 15 the grinding element, and its combination with the main truck frame on which it is mounted. This arrangement is a special feature of applicant's invention and was invented with a view to the securement of 20 ready manipulation and adjustment, and efficient operation.

In the application referred to, and in the accompanying drawings, I show only one 25 form of grinding element, to wit: a reciprocating form, and further I show as a whole, only one embodiment of my invention. But I desire to have it understood that in its broad aspect, my invention is not limited to one form of grinding element, nor is it capable of one embodiment only. Other forms of 30 grinding element might be substituted for the reciprocating grinding element, and my invention as a whole might be given any one of several embodiments by those skilled in 35 the art without departing in any wise from its limits.

Of the accompanying drawings: Figure 1 is a view of a portion of Fig. 1^a of the parent application showing the grinding element in side elevation, Fig. 2 is a view of a 40 portion of Fig. 2^a of the parent application showing the grinding element in plan, and Fig. 3 is a transverse section of the grinding element and its mounting after Fig. 5 of the parent application. Figs. 4 and 5 are 45 respectively longitudinal and transverse sections of the brick holder and connected parts, showing the means for canting and adjusting the bricks.

50 All of the parts are numbered as in the parent application.

The sides 29 of the main truck frame are extended forwardly and embrace the truck wheel 5 journaled between them. The rear

truck wheels are not shown in this application, but they are secured to the frame members 29 and support the frame on the trackway in a manner entirely similar to that in which the truck wheel 5 is secured to the sides of the frame, and bears upon the trackway. The details of this construction will not be entered into here.

In proximity to the wheel 5, the upper and lower flanges of each of the side members are provided with smooth slides 18 and 19, upon which rest the guides 20, 21, 22, 23, 24, 25 and two others not shown, attached to the carriage 26, which forms the reciprocating element of the machine and has at one end a pair of ears 27 to receive the pivotal 70 end of a connecting rod which is journaled on the truck frame to reciprocate.

Returning to the reciprocating carriage 26, this is fitted with vertical end slides 42 and 43, which enter guide slots formed vertically in the ends of a heavy block or brick holder 44. This block is an iron frame and is purposely made massive so as to exert heavy pressure upon the grinding surface in operation. It is free to slide up and down 80 in the carriage, its weight being normally supported entirely on the grinding bricks 45 as they rest upon the rail. In order to raise it out of engagement with the rail when the machine is to be moved or for purposes of 85 inspection, the brick holder is provided with trunnions 46 and 47, upon which are pivoted a pair of cams 48 and 49, secured to and operated by a pair of connected levers 50 and 51, whose return bar or handle 52 90 constitutes in effect a bail which normally lies flat as shown in Fig. 1, across the top of the end piece 3 of the frame, where it is entirely out of the way. On lifting up the bail however, the cams 48 and 49 are turned 95 upon the trunnions 46 and 47, and lift the block 44 together with the grinding bricks and other attachments thereon, and when the bail is thrown over past center, the cam rests on its reverse face, so that the block 100 will be held up automatically as long as desired.

The block 44 is a frame with a rectangular opening extending through it from top to bottom, and an enlarged opening or openings extending into it from beneath for the reception of a longitudinally pivoted swinging brass box containing the grinding bricks

45. These bricks are spaced apart by shims or distance pieces 53, are adjustable by and receive pressure through wing bolts 54 threaded into bridges 55; and they are all 5 locked into position when adjusted by means of a movable wedge 56 coöperating with a fixed wedge 57, between the end brick and the inner face of the end of the holder, the movable wedge being forced down into locking position by the bolt 57^a having a T-handle 58 and lock-nut 59.

The brass box or frame containing the bricks is indicated at 161 in Fig. 1, and is pivoted on massive trunnions shown at 162 15 and 163 in Fig. 4 in bearings in the block 44. It is canted for oblique grinding, by means of the two nuts 164 and 165 threaded on a bolt 166 sliding through the bosses 167 and 168 and secured intermediate of said bosses 20 in a head 166^a projecting upwardly from the box 161. The bricks can thus be set at any angle, as the frame is rocked on its trunnions. The advantages of this should be 25 most readily apparent, for not only does this provision make it possible to grind rail surfaces at any angle to the horizontal and to the plane of the main truck frame, but grinding on curves is facilitated, and grinding of edge and trough irregularities may 30 be most readily accomplished.

I desire to cover in the annexed claims, all embodiments which my invention may be given by those skilled in the art.

Having thus described my invention what 35 I claim and desire to secure by Letters Patent is:

1. A rail grinding machine comprising a frame, means for supporting the same over a rail to be ground, and a grinding element 40 secured on the frame with means for transverse angular adjustment thereon, for oblique grinding of the rail surface.

2. A rail grinding machine comprising a main truck frame, a grinding element on 45 said frame mounted in a longitudinally extending vertical plane for movement about a longitudinal axis, and means for canting said grinding element laterally of said plane.

3. A rail grinding machine comprising a main truck frame and wheels adapted to travel over a trackway, a grinding element mounted thereon for movement about a longitudinal axis, said grinding element lying normally in a plane parallel to the plane of the wheels on one side of the truck, and said longitudinal axis lying on one side of 55 said truck frame and adjacent said plane.

4. A rail grinding machine comprising a main truck frame, a grinding element on 60 said frame, mounted in a longitudinally extending vertical plane for movement about a longitudinal axis, and means operative independently of the trackway for canting said grinding element laterally of said plane.

5. A grinding machine having a truck frame, track wheels, a grinding element, an auxiliary frame carrying said grinding element, means to drive the auxiliary frame and grinding element, and means for obliquely adjusting the element in the auxiliary frame. 70

6. A grinding machine having a truck frame, track wheels, guides on the frame, an auxiliary frame arranged to travel in said guides, means to drive the auxiliary frame, a holder pivoted in said auxiliary frame for oblique adjustment with respect to the rail surface, and a grinding element in said holder. 75

7. A rail grinding machine comprising a main truck frame and wheels adapted to travel over a trackway, an auxiliary frame connected with said main frame, and vertically movable with respect thereto, a 85 grinding element mounted thereon for movement about a longitudinal axis, said grinding element normally occupying a longitudinally extending vertical plane, means for moving the auxiliary frame vertically, and independent means for canting the grinding element by movement about the longitudinal axis. 90

8. A rail grinding machine comprising a main truck frame and wheels, a grinding 95 element connected with the frame normally occupying a plane parallel to the plane of the wheels, and means acting on a line transversely of said main truck for canting said grinding element out of its normal plane. 100

9. A grinding machine having a truck frame, track wheels, guides on the frame, a carriage arranged to travel in said guides, means to drive the carriage, a holder pivoted in said carriage for oblique adjustment with respect to the rail surface, and a grinding element in said holder, together with means for locking the holder and grinding element in adjusted position. 105

10. A grinding machine having a truck 110 frame, track wheels, guides on said frame, a carriage fitted to said guides, a box or holder mounted on trunnions in the ends of said carriage, grinding means secured in said box or holder, and a transverse screw 115 connection between the box or holder and the carriage on a line eccentric to the axis of the trunnions, with locking means for said screw connection, whereby the box or holder may be laterally adjusted in the carriage 120 for the oblique grinding.

11. A grinding machine comprising a frame, track wheels and a grinding element, means for adjusting said grinding element obliquely on the frame, and means for producing a relative lateral adjustment between the grinding element and the track wheels to change the alinement for grinding on curves and the like. 125

12. A grinding machine comprising a 130

frame, track wheels for supporting the same over a rail to be ground, a grinding element on the frame held in alinement during grinding by said wheels, and supported thereby in proper relation to the surface of the rail, and a rotary cam or eccentric acting against the support of the wheels to raise and lower the grinding element vertically with respect to the rail, when the cam is turned in one direction or the other.

13. A grinding machine comprising a frame, track wheels for supporting the same over a rail to be ground, a grinding element on the frame held in alinement during grinding by said wheels, and supported

thereby in proper relation to the surface of the rail, means for obliquely adjusting said grinding element on the frame, and a rotary cam or eccentric acting against the support of the wheels to raise and lower the 20 grinding element vertically with respect to the rail, when the cam is turned in one direction or the other.

In testimony whereof I affix my signature in presence of two witnesses.
